[57] CLAIM

The ornamental design for a combined lamp and identification sign, substantially as shown and described.

DESCRIPTION

FIG. 1 is a perspective view of the combined lamp and identification sign showing my design;

FIG. 2 is a top plan view thereof on an enlarged scale;
FIGS. 3 and 4 are respectively front and rear elevational views on an enlarged scale.

The indicia and light source are shown in broken lines for illustrative purposes only. The post is broken away to indicate indeterminate length.
